MULTIPLE FUSE CONTROL MECHANISM IN
COMBINATION WITH THERMOPROTECTIVE SIGNAL SYSTEM

Abel U. Breune, Brooklyn, N. Y.

Application April 9, 1936, Serial No. 73,406

21 Claims. (CL 200—113)

My invention relates to improvements in electric circuit overload devices, and has for one object the provision of the combination of a standard fuse, of the cartridge type, embracing a new 5 fuse-element operative with a bimetallic thermo-responsive means, to be installed as a unit as a multiple fuse protection for electric lighting, motors, and other electrical machinery in branch circuits; or if used in main-feeder wiring protection having an accessory assembled device, manually controlled and mutually constructed for prewarning thru signal or annunciator against overloads, unbalanced loads, or irregular peak-loads in electrical circuits and mains.

15 Another object of the invention is to provide for a pre-determined setting of calibrated limits, the peak-load and "maximum-demand" use of electricity, and the control of varying methods of operation of electrical machinery in commercial plants.

Another object of the invention is to provide means for shunting the weakest point on the fuse member by the use of a bi-metal member.

A further object is to provide means for maintaining the said bi-metal member from contacting or uniting the two parts of a blown fuse.

Another object of the invention, provides the means of a fuse protection of the variable load characteristics in circuits, providing a combination fuse for heavy-duty overload starting current of motors, and a lower amperage fuse protection for running characteristics in motor circuits, constructed in one fuse element.

Another object of the invention is to provide a 35 fuse element and a bi-metal unit jointly cooperating in principle, "in the thermal conductivity of the fuse element," resulting in a variable expansion movement of the bi-metal unit, to permit a multiplicity of uses thereof.

40 Another object of the invention, provides the use of a supporting insulated fibrous strip secured to the fuse, protecting the molten fragmentary metal from coming in contact with other metallic parts in the fuse, if and when said fuse melts due to a short-circuit or dangerous overload, or prevents same from unnecessary warping within fuse-shell, and also provides a means for insulately separating the current flow thru fuse if and when same volatilizes with an overload or short-circuited condition.

A still further object of the invention provides the use of a standard refillable cartridge fuse element, having a new and novel construction of plurality amperage-ratings in the same fuse-element operating jointly with a bi-metal unit

secured to it; same may be placed or interchanged in any standard cartridge-fuse, fuse-block, switchboard, cutout, service-switch, or standard motor control apparatus.

Fuses installed in electric circuits and main-feeders are definite protectives against overloads and short-circuits. However, such fuses fail in part, in that in practice, circuits and feeders are necessarily largely overfused or improperly fused, and as a consequence electrical machinery, 5 motors, transformers, and other electrical appurtenances are frequently incapacitated, especially those requiring varying starting and running-load amperages, the fuses being excessively oversized to allow greater starting amperages, resulting in burned out equipment, causing needless replacements, repairs, and costly delays. The many present inventions and commercial devices in electric current control, designed to interrupt and regulate the flow of current in circuits now in 10 use are only coordinated devices used in circuits necessarily overfused.

As a new and novel invention for overload circuit prevention, I introduce a refillable or renewable type fuse combination which will automatically compensate abnormal starting current requirements, and also provide the necessary and safe normal fuse protection. Standard fuses in use are rated in amperes, and its fuse element construction consists of a "cut" or "notch", or tapering down to a reduced thickness in circular-mils rating in accordance with the designed amperages. My invention consists of a fuse-element 15 having a plurality of "notches," but which notches are sized in thickness or circular-mil of variable 20 and intermediate ampere-ratings resulting in a multiple current resistance variability in the same fuse-element; and it is operative integrally with a bi-metal expansion unit or strip, engaged 25 in a synthermal relationship to function in a 30 multiple of applications.

The invention is entirely free from any electrical relays or electro-magnetic devices, and provides no mechanism which directs the flow of current in circuits, except as to the electrical resistance in the fuse element itself. The distinctive features lie substantially in principle in the thermo-generation and heat-retention of the fuse-element itself, and a co-acting thermo expansive bi-metal unit synthermally related. If 35 the invention be used in main-feeder wiring protection, the assembly of a time-limiter and regulator provides means whereby pre-arrangedly, 40 and prior to the "fusing" or melting of the fuse-element, a signal or annunciator becomes opera- 45 50 55

tive, and affords the opportunity for the commercial plant attendant or management, and upon suitable signal indication to correct and reduce the overloaded or critical situation in the system, and accordingly precludes the hazards of burn-outs and serious damage to the electrical equipment.

With the foregoing general explanation and other details in view, the invention consists of 10 a novel construction, combination and arrangement of parts as will be more specifically described and illustrated in the accompanying drawing wherein is shown an embodiment of the invention, but it is understood that modifications, variations and alterations can be resorted to, which lie within the scope of the invention and the claims hereto appended.

In the accompanying drawing, Fig. 1 is a front elevational view of the device, showing a standard cartridge fuse, but with indicator attached.

Fig. 2 is a longitudinal sectional view thereof.

Fig. 3 is a sectional view on line 3—3 Fig. 1.

Fig. 4 is a fragmental sectional view showing the reserve plunger in position when the fuse has 25 blown.

Fig. 5 is a fragmental sectional view of the attachable indicator mechanism enlarged, and

Fig. 6 is a partial switchboard construction showing both individual branch circuits and the 30 main feeder fuses provision, and the wiring arrangement of low-voltage current transformer and signal and annunciator system.

Referring now to the drawing in detail, 10 indicates the fuse shell constructed of fibre, "Bakelite", or any refractory substance of non-metallic material, preferably cylindrical in form, comprising two end-ferrule caps 11, interiorly threaded or provided with other means to secure same to the cylinder shell 10, and containing 15 within said shell suitable means for making interiorly solid connection electrically and mechanically to a fuse-element 15. If the fuse is to be used in main-feeder circuit protection, said fuse-shell 10 may be provided on its face with an insulated rotating regulator 12, comprising a screw 24 carrying an extended arrow-pointer 13, with suitable legends indicated at 30 on said shell 10 over the arrow-pointer. The rotating regulator 12 also carries an extension-piece 32 having a 20 screw terminal 14 to which is connected a wire 23 which is electrically connected to the time-limiting screw 24, the rotating of the latter creates a forward or backward movement depending upon the time-limit desirability of contacting with the bi-metal unit 16 at 33. The extension piece 32 is held in place against the fuse shell by any suitable means at one end and it is provided at its opposite end with a hole 32, thru which 25 time-limiter 24 is manually set and screwed thru the shell of the fuse, interiorly, to subsequently connect with the bi-metal member 16 at 33. The construction of the time-limiter may be modified in many adaptable forms provisioned with insulated members, having a standard thread and may easily be engaged or disengaged with a screw thru the fuse-shell 10, for the purpose of interchanging the fuse from use in branch circuits without time-limiter engagement, or may be installed in main-feeder circuits with time-limiter 30 installed as an integral unit.

With the installation of the time-limiter mechanism in the fuse, it becomes apparent that it is installed to make an electrical connection with 75 the current in the system to the wire 23 for the

purpose of connecting with a low-voltage transformer 26 (see Fig. 6) and then thru to annunciator 28 and signal 27. But since wire 23 is only one side of a connection, I provide the return wire 33 from any suitable neutral, or "ground" wire 5 in the system which will connect to transformer 26, as shown at 33. The electrical connection of wire 23, thru 32, and then thru time-limiter 24, will eventually complete the electric circuit, if and when bi-metal 16 at 33 will expand or warp 10 sufficiently to contact time-limiter 24. When it has become so engaged electrically, the current passing thru it has the same potential or voltage as in the system, and with the neutral wire connection as described above completes the circuit 15 to operate the annunciator and signal system for which this invention was designed. To suggest several variety wiring arrangements, I specifically include low-voltage, transformer, and annunciator, the latter to indicate the particular side of 20 line overloaded, but it is obvious that any electric signal, alarm, gong, pilot-light, or other indicating electrical devices may be direct-connected with the voltage in the line, to signal the overloaded or dangerous condition in the system. 25

The fuse-element construction 15, as shown in Fig. 2, being a renewable type, has extending ends or ears 31 and 31a to engage mechanically and electrically to end caps 11 as generally provided in refillable cartridge fuses; secured to said fuse-element is a separate flat non-conductive fibrous or hard-rubber strip 35, secured by rivets or otherwise as 18 and 18a which is intended to reinforce the fuse-element 15 in its entirety within the fuse-shell against warping, and it also provides means for preventing parts of the fuse-metal from disintegrating and contacting the molten fuse with other parts of metal within fuse-shell in the event of a short circuit in the system. 40

The fuse-element 15 is also provided with a plurality of "notches", or tapering down to a plurality of V shaped cutouts on the longitudinal side edges; such V notches having varied circular-mil fuse ratings, or "ampere calibrations" 45 as indicated by 19, 20, 21, and 22 in Fig. 2. By different sizes in ampere calibrations I mean a plurality of different (circular-mil) amperage size construction in the same fuse-element. The arrangement in the variable amperage calibrations in the one fuse element is to be made in the most practicable form for use in approximately the same regulatory manner as is now used in fuse protection of circuits and main-feeder installations. As indicated in Fig. 2, the upper 50 V notch 19 and the lower one 22, I provide with larger amperage calibrations, and the two inner ones 20 and 21 with the smaller rated amperages. If the starting current of an electric motor for instance, required 100 amperes, and the running 55 normal current only 60 amperes to safeguard this motor, I would construct the fuse-element in the following manner:—at 19, 100 ampere rating; at 20, 75 ampere rating; at 21, 60 ampere rating; at 22, 90 ampere rating. It is to be noted however, 60 the above is only suggestive, and I may construct a variety of amperage values in the same fuse-element to meet any particular requirement.

As is known, fuses installed in electric circuits being the weakest link in that circuit, will "blow" 70 at a dead-short or when the current is the same or greater amperage than the fuse rating. When the current is zero, the fuse-element is entirely "cold" thermostatically. As we subject the circuit with an amperage, the fuse element having 75

a definite electrical ohmage or resistance, sets up a thermal condition, of and within itself;—a heat corresponding to the amperages superimposed and prolongingly sustained in the circuit; the said heat being proportional to the increase or decrease ampere-load; and if an overload or critical condition be created larger than the rated amperes, the fuse when reaching a melting temperature destructively "fuses", snapping the circuit open.

As shown in Fig. 2, the bi-metal expansion strip 16 is secured at one of its ends to the fuse 15 by a rivet or fastening 17 and runs parallel and in close proximity thereto, within the fuse shell, said bi-metal expansion element overlapping snugly one or more variable amperage calibrations in the fuse-element. This bi-metal strip 16 being of a certain thickness, consists of an alloy of two-metals having different coefficients of heat expansion; and the preferred bi-metal I use is one of quick-responsiveness to heat treatment. Now the heat generated is superimposed in the fuse-element because of the amperage flowing thru it, faithfully reproduces itself in the thermostatic bi-metal unit 16, which is welded or riveted at one end for instance snugly to it, and causes the loose-end 33 of the bi-metal to expand in a "curved-movement" therebeyond, and gradually expanding to the time-limiter 24 connected therethru to indicator 12 on outside of fus shell 10. The free end 33, will definitely warp in a curved movement, responding synthermally with the permeated heat and the heat retention by the fuse-element 15, or it will straighten itself out, flat, snugly and parallelly with the fuse element, when the current is reduced and the heat in the fuse approaches zero.

Reserved for instant use, and movable thru a recess 36 in the strip 35 is an insulated plunger which is controlled by the tension of a spring 29 secured at one end thereof to the strip 35 by the rivet 17. The reserve insulated plunger 34 is at right angles with fuse-element 15 on face 45 side of strip 35, and is held normally rearward, in tension, between the resiliency of the fuse element on one side of strip 35, and the spring 29 on the other. The reserve-plunger only becomes operative, automatically, when the amperage calibration at 21, being the smallest and weakest of the whole range of amperage sizes in the fuse-element, breaks open. If a ruptured current or short-circuit takes place, it will automatically press thru recess 36, elevating the bi-metal end at 33 away from its position; the fuse element at 21 now being broken away and volatilized with the short-circuit, offers no further resistance, and accordingly, allows the insulated plunger to function instantly. Irrespective in 50 what position the bi-metal 16 is held, either contracted (flat) and parallel with fuse element, or expanded outwardly (by the heat) in the space-gap toward time-limiter 24, the reserve-plunger will definitely separate at its lower or 55 spring end and insulate the bi-metal from further contact with the remainder of the fuse. If a prejudicial current be subjected in the circuit, the reserve plunger keeps the circuit open and interrupted, until a new fuse-element be placed in the fuse.

The time-limiter 24 is so made that it may be readily inserted into or removed from the fuse-shell 10. The elongated metallic threaded screw mechanism installed transversely thru shell 10, 75 can be manually moved forward or backward,

predeterminately, and is adjustable thereto with set-screw 12a. When the time-limiter 24 is fixedly set, it of course provides a definite space-gap or zone, which is intended to gauge the time limit with which the bi-metal end 33 is ultimately to be connected, if and when the latter expands with the imposed heated condition therein. When the thermostatic bimetal has expanded, it bridges and contacts the end 33 with the limiter 24, connecting the electric current in the system, passing thru to extension piece 32 and then to wire 23, which as shown in Fig. 6 is connected with a low-voltage transformer 26 continued to a signal 27, and annunciator 28; the return wire to complete the circuit being connected with the voltage in line or with any neutral or "ground" in the system.

In Fig. 6 there is shown a diagrammatic arrangement of a sectional open switchboard construction 25 with the main feeder fuses together with branch circuit lines 39. Also wiring connections of low-voltage transformer 26, annunciator 28, and signal 27. It will be noted that the latter may be combined and installed at any remote place from the switchboard, found to be the most suitable location for the particular enterprise.

As stated the bi-metal expansion unit 16 becomes operative only with the permeated heat in the fuse-element or with an inconsequential current flowing thru it, the bi-metal 16 does not expand, and overlaps V 20 and V 21, differently rated, but smaller amperage values than V 19 and V 22 and accordingly "short-circuits" or shunts these two under-disposed amperage ratings, the current passing thru the bimetal 16 simultaneously with the fuse at V 19 and 22, the larger rated amperage V's being now left to protect the circuit. The amperage ratings of the latter two V's are sufficiently large to sustain an abnormal starting current load within the proximity of the heavy duty starting demands made of it; as for example, the starting of an alternating current motor requiring about 200% greater amperage than normal running current. In actual application, the starting of a motor causes a momentary sudden rush of a heavy current in the circuit, likewise impressed in the fuse, and were the two smaller amperage rated V's at 20 and 21 not reinforced and short-circuited or shunted by the bi-metal 16, they would necessarily "blow" at the starting instant. As can be apparently noted, the smaller rated amperage V's being short-circuited and not of a material consequence at the motor starting, the heavier rated amperage V's at 19 and 22 are now purposely overfused within safe limits of motor starting requirements.

It must be borne in mind, however, that the sudden abnormal starting current impressed in the circuit is only—momentary; and as the motor soon speeds up to normal current requirements, usually only a matter of seconds, it does not create an appreciable thermo-condition in the fuse, at the starting instant; nor sufficiently to conduct and cause the "curve-action" of the bi-metal unit 16 secured to it. However, as the current requirement of the motor soon becomes normal, it does cause a thermo status in the fuse-element, permeating a heat magnitude in ratio with the sustained amperage in the circuit, and accordingly impregnates by conduction a syn-thermal relationship in the bi-metal 16, causing it to form a warped curve-motion 16a, as shown in Fig. 3. The expanded curve-motion starts at 33 moving outward and away from fuse 15 to the hinged end at rivet 17, protruding into space-gap 75

or zone toward limiter 24. As it does so, it separates itself from contact at 20 and 21, the smaller rated amperages in the fuse. The fuse now has become once again with the smaller rated amperages the major and predominating protection in the circuit; but it is the safest protection necessary to properly safeguard the electrical wiring and machinery in the line. If a prejudicial current be introduced suddenly while the motor is running, it is obvious that the smaller rated fuse-amperages (now free and not short-circuited) will be first to blow in the circuit. It must be noted, that whereas the smaller rated fuse-amperage is the exact and true protection for the normal rating and requirements of the electrical machine, contradistinctive to the average present uses of fuses, with the detrimental over-fused consequences, my invention resides in an absolute improvement over present fuses or accessory over-loading devices now used in electrical circuits. It will also be noted that the installation of the variable fuse protection of this invention will not only give safer normal running current protection, but will also automatically compensate means for overloaded and abnormal starting characteristics of electrical machinery.

As another application in the use of this invention, it will be noted that same may be installed at switchboard for main-feeder protection of the entire electric load in a commercial plant. The many and irregular methods of electrical machinery operation affects the fuse-element—thermostatically. Fluctuating and variable temperatures in fuses at the main switchboard are caused by starting and stopping of motors; split-phasing; variable-impressed voltages; variable motor loads; partial openings in the line of motors; motors running with low bearings, the rotor being out of center; increasing loads of special electrical machinery, and other conditions too numerous to mention here. Fuses installed at the main-service switch, cutout-block or switchboard are subjected to the entire load of the whole plant, circumventing not only the fluctuating conditions above mentioned, but the vast number and different kinds of motors and machinery employed, and the variable lighting and heating loads in plants. The thermo-responsiveness of these main fuses registers a continuous heat rise and cooling effect, alternately corresponding as the load is increased or decreased, and as the conditions be existent in the system.

In line with the above conditions, the installation and use of my invention tends to minimize the electrical malpractices or abuses in plants, and resides in the utilization of controlling at any pre-determined arrangement, a definite understanding with peak-load operating limits, and "maximum-demand" practices of electricity and electrical loads. The flexibility with which anyone inexperienced in the art may control pre-arangedly any load limits, setting the indicator 12 and time-limiter 24, so as to permit, by the movement forward or backward of same to the desired definite limits with which bi-metal at 33 expanding with the load will connect with it. Connecting both bi-metal 16 and time-limiter 24 completes the circuit to automatically signal the attendant when the peak-load has been attained. As will be seen, this automatic operation requires little plant supervision and automatically registers signally a pre-determined peak-load, and accordingly enables the plant-management to "systematize" or "regulate" the electrical efficiency of his establishment.

Where it is desired to use my invention of multiple-fuse protection in single motor circuits, other than main feeder protection, (considering of course that the rated amperage of the motor is within the maximum proximity of fuse-rating) it will be seen that there be no requisite for indicator 12 and time-limiter 24 construction; and my invention resides in the flexibility of disengaging or unscrewing this assembly in the fuse shell 10. Thus it is noted that the device is interchangeable in use from main-feeder protection to branch circuit protection, and vice-versa; it offering the feasibility of multiple fuse protection, as well as the main control with the time-limiter assembled as shown in Fig. 3.

To summarize the various characteristics of my invention, it must be understood that same is not limited in use or construction or application; that it is interchangeable with any cartridge fuse, open fuse block, cutout, switch in branch-circuit or main feeder fuse protection; that as a fuse-element in combination with a thermo bi-metal function, it incorporates a multitude of uses; that same is compactly constructed as a unit for quick replacements in standard cartridge fuse shells and in the variety of fuseblocks used and that modification of detail and construction is hereby reserved so long as it conforms within the scope of the invention.

Having described my invention, what I claim as new and desire to secure by Letters Patent is:

1. A fuse, comprising a fusible strip having spaced apart electrically weakened areas and a bi-metal expansible strip secured to the fusible strip, overlying one surface of the said strip and shunting some of the said weakened areas.

2. A fuse, comprising a fusible strip having spaced apart electrically weakened areas, a bi-metal expansible strip secured to the fusible strip, overlying one surface of the said strip and shunting some of the said weakened areas and a strip of insulating material secured to the fusible strip at its opposite surface.

3. A fuse, comprising a fusible strip having spaced apart areas of various electrical current carrying capacities and a bi-metal expansible strip secured to the fusible strip overlying one surface of the said strip, and shunting some of the said weakened areas, the fusible and bi-metal strips being syn-thermal.

4. A fuse, comprising an insulating cartridge shell, metallic caps at each end thereof, a fusible strip in electric contact with the caps and having spaced apart electrically weakened areas and a bi-metal expansible strip secured to the fusible strip, to shunt some of the said weakened areas.

5. A fuse, comprising an insulating cartridge shell, metallic caps at each end thereof, a fusible strip in electric contact with the caps and having spaced apart electrically weakened areas and a bi-metal expansible strip secured to the fusible strip, to shunt some of the said weakened areas when below a predetermined temperature, the fusible and bi-metal strips being syn-thermal.

6. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, an insulating member secured to the fusible strip, and a spring pressed plunger of insulating material slidably mounted in the insulating member in line with the weakest area of the fusible strip for the purpose specified.

7. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, and indicator energizing contact means for contacting the free end of the bi-metal strip when same is heated and in warped position.
8. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, indicator energizing contact means for contacting the free end of the bi-metal strip when same is heated and in warped position, and a spring pressed plunger in line with the weakest area for preventing the return of the bi-metal strip to flat position when same is cold and the fusible strip has blown.
9. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, a screw extending into the interior of the shell, in line with the free end of the bi-metal strip, and an electric contact in engagement with the said screw and an independent circuit closing lead wire secured to the said contact.
10. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, a screw extending into the interior of the shell, in line with the free end of the bi-metal strip, an electric contact in engagement with the said screw, an indicator lead wire secured to the said contact, a pointer carried by the screw and indicia on the shell in operative relation to the pointer for the purpose specified.
11. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, a screw extending into the interior of the shell, in line with the free end of the bi-metal strip, an electric contact in engagement with the said screw, an indicator lead wire secured to the said contact, a pointer carried by the screw, indicia on the shell in operative relation to the pointer for the purpose specified, and means for adjusting the inward extension of the screw.
12. A fuse, comprising an insulating cartridge shell, metallic caps at each end thereof, a fusible strip in electric contact with the caps and having spaced apart electrically weakened areas, a bi-metal expansible strip secured to the fusible strip, to shunt some of the said weakened areas, and an energizing indicator mechanism removably mounted on the shell and partly extending to the interior thereof in line with the free end of the bi-metal strip.
13. A refillable type fuse for an electric circuit having variable starting and running characteristics, comprising in combination a fuse-element of multiple fuse areas of varying electric current carrying capacities, standard terminal-ends to adapt same for installation with a fuse reception means, and a bi-metal unit jointed to said fuse-element, the jointed combination fuse-element and bi-metal unit so synthermally operative that a current flowing thru the circuit will permit the sequence: (1) heavy duty fuse protection for the abnormal momentary-excessive starting current requirement, and (2) the smaller normal-running fuse protection in fuse-element for the normally sustained current requirement of a circuit, the said sequence maximum and minimum fuse-strength and resulting combinations at the different starting and normal-running intervals varying with the permeated and sustained thermic condition of both fuse-element and bi-metal unit, mutually and synthermally combined.
14. A refillable type fuse for an electric circuit having variable starting and running characteristics, comprising in combination a fuse-element of multiple fuse areas of varying electric current carrying capacities, standard terminal-ends to adapt same for installation with a fuse reception means, a bi-metal unit jointed to said fuse-element, the jointed combination fuse-element and bi-metal unit so synthermally operative that a current flowing thru the circuit will permit the sequence: (1) heavy duty fuse protection for the abnormal momentary-excessive starting current requirements, and (2) the smaller normal running fuse protection in fuse element for the normally sustained current requirement of a circuit, the said sequence maximum and minimum fuse-strength and resulting combinations at the different starting and normal-running intervals varying with the permeated and sustained thermic condition of both fuse-element and bi-metal unit, mutually and synthermally combined, and means operatively associated with the bi-metal unit which when contacted by the said bi-metal unit will energize a signal indicator.
15. A fuse, comprising a fuse element having a plurality of fuse areas of varying amperage ratings, and a bi-metal strip secured to the fuse element to shunt some of the said areas when the bi-metal strip is substantially cold.
16. A fuse comprising a fusible strip having spaced apart areas of varying electrical current carrying capacities, and a bi-metal expansible strip secured to the fusible strip overlying one surface of the strip and shunting some of the said areas.
17. A fuse comprising a fusible strip having spaced apart areas of varying electrical current carrying capacities, and a bi-metal expansible strip secured to the fusible strip overlying one surface of the strip and shunting some of the said areas, the current passing through the said areas creating a rise in temperature causing the bi-metal strip to warp away from the fusible member.
18. A fuse comprising a fusible strip having spaced apart weakened areas, and a bi-metal expansion strip secured to the fusible strip and shunting some of the weakened areas, the said bi-metal and fusible strips being syn-thermal.
19. A fuse comprising an insulating cartridge shell, metallic caps at each end thereof, a fusible strip having spaced apart areas of varying electrical current carrying capacities, and a bi-metal expansible strip secured to the fusible strip overlying one surface of the strip and shunting some of the said areas.
20. A fuse comprising an insulating cartridge shell, metallic caps at each end thereof, a fusible

strip having spaced apart areas of varying electrical carrying capacities, and a bi-metal expansive strip secured to the fusible strip overlying one surface of the strip and shunting some of the said areas, the current passing through the said areas creating a rise in temperature causing the bi-metal strip to warp away from the fusible member, the said bi-metal and fusible strips being syn-thermal.

21. A fuse, comprising a fuse element having a plurality of fuse areas of varying amperage ratings, a bi-metal strip secured to the fuse element to shunt some of the said areas when the bi-metal strip is substantially cold, and means adapted to be contacted by the free end of the bi-metal strip when the said strip is heated and warped from the fuse element. 5

ABEL U. BROUINE.
